UNITED STATES PATENT OFFICE.

JOHN DI PIAZZA, OF NEW YORK, N. Y.

CLEANING DEVICE.

1,409,234.

Specification of Letters Patent. Patented Mar. 14, 1922.

Application filed January 27, 1921. Serial No. 440,388.

To all whom it may concern:

Be it known that I, JOHN DI PIAZZA, a subject of the King of Italy, and resident of the city of New York, borough of Manhattan, in the county and State of New York, have invented a new and Improved Cleaning Device, of which the following is a full, clear, and exact description.

My invention relates to a cleaning device, and aims to provide an element of this nature, particularly adapted to clean brushes.

It is a well appreciated fact that it has been customary, in connection with brushes, to provide elements in the nature of combs, the teeth of which have been passed through the body of the brush, for removing foreign matter, such as hair, etc. from bristles of the same.

This cleaning action has been necessarily limited, particularly when hair, dandruff, etc., was to be cleaned from the brush, in that these foreign elements have been intertwined and in intimate contact with the bristles.

With this in view, I have constructed a cleaning device, and an object of my invention is the provision of an element of this nature in which all foreign matter will be effectively removed from the bristles of a brush.

A further object of my invention is the construction of a cleaning device in which it will not be necessary to exert as much force to clean the bristles, as has been heretofore necessary, so that the wear upon the body of the brush, incident to this action, is reduced to a minimum.

Another object of the invention is that of providing a device of the character stated, which shall be extremely simple in construction and operation, so that the same may be placed upon the market at a minimum figure, and be free from mechanical troubles.

Other objects of my invention will appear in the annexed specification and drawings, which latter present one practical embodiment of the same, and in which—

Figure 1 is a sectional side view of a cleaning device constructed in accordance with my invention.

Figure 2 is a sectional plan view of the same taken along the lines 2—2 and in the direction of the arrows indicated in Figure 1.

Figure 3 is a sectional end view taken

along the line 3—3 and in direction of the arrows also indicated in Figure 1, and

Figure 4 is an enlarged fragmentary sectional view of one of the details of my invention.

Referring now more particularly to Figures 1 and 2, it will be seen that my device preferably includes a casing 5 upon the upper face of which supporting brackets 6 may be affixed, said supporting brackets being adapted to engage and retain a brush 7 of any desired type in applied position thereon.

It will also be noted that the upper face of the casing 5 may conveniently provide a series of longitudinally extending slots 8 which under lie the bristles of the brush 7. Also a series of cleaning elements 9 are positioned within the body of the casing 5 and provide teeth, which latter are curved and extend through the slots 8, in the upper face 75 of the casing 5.

With a view of actuating the cleaning elements 9, which correspond in number to the number of slots 8 provided, I preferably mount the same upon a shaft 10, which latter is provided with gears 11 adjacent its end portions, these gears being engaged and supported by tracks in the nature of serrated bars 12.

Thus it will be obvious that upon a rolling contact being established between the gears 11 and bars 12 that the shaft 10 and cleaning elements 9 carried thereby will be caused to move longitudinal of the casing 5, and at the same time, the cleaning elements will be rotated. Now with a view of providing means serving to accomplish this movement, I preferably utilize an endless member in the nature of a sprocket chain 13, which passes around gears 14 rotatably secured adjacent the ends of the casing, and a rack 15 engaging a gear 16 mounted upon the shaft forming a supporting element for one of the gears 14 will serve to effect a movement of the chain 13 upon the same being projected or retracted.

Suitable means for accomplishing this latter motion are provided by utilizing a handle 17 secured to the outer end of a bar 18 forming a continuation of the rack 15, and a spring 19 co-operating with the handle 17 and bar 18 serves to return these elements to their normal position subsequent to the handle having been depressed.

Thus it will be seen that upon the handle 110

17 being projected downwardly, that the rack 15 will cause a movement of the chain 13, and this element being coupled to the shaft 10, as by means of the bearing 20, it 5 will be obvious that the shaft 10 will be moved longitudinal of the casing 5, which by virtue of the motion aforescribed, will result in a rotation of the cleaning elements 9, and a consequential co-operation between 10 these elements, and the bristles of the brush 7, it being noted that the handle 17 upon being released will return to its normal position by virtue of the connection of the spring 19, this insuring a return of all of the parts 15 to their initial position.

From the foregoing it will be appreciated that I have constructed a cleaning device, more particularly adapted for use in connection with all classes of brushes, but more 20 particularly for use in connection with the cleaning of hair brushes, and it will be obvious that by means of the structure described, that these brushes may be cleaned in a most desirable manner, and within a 25 minimum space of time, which is to be particularly desired, where the device is utilized in barber shops.

It will also be understood that numerous modifications of structure might readily be 30 resorted to without in the least departing from the spirit of my invention, which I claim as:

1. A cleaning device including a casing formed with openings, cleaning means within 35 said casing and extending through said openings, and means for actuating said cleaning means and being adapted to move said cleaning means longitudinally and rotatably with respect to said casing for en-

gaging the bristles of a brush positioned adjacent said casing and removing foreign particles therefrom.

2. A cleaning device, including a casing provided with slots in one of its walls, tracks within said casing, a shaft also within 45 said casing, cleaning elements mounted upon said shaft and extending through said slots, and means for moving said shaft upon the tracks.

3. A cleaning device, including a casing 50 provided with slots in one of its walls, tracks within said casing, a shaft also within said casing, cleaning elements mounted upon said shaft and extending through said slots, and means for moving said shaft 55 upon the tracks and in rolling contact therewith.

4. A cleaning device, including a casing provided with slots in one of its walls, a shaft positioned within said casing, cleaning elements mounted upon said shaft and extending through said slots, gears secured to the ends of said shaft, tracks presenting serrated upper edges adapted to be engaged by said gears, and means for moving said 65 shaft along said tracks.

5. A cleaning device, including a casing provided with slots in one of its walls, a shaft positioned within said casing, cleaning elements mounted upon said shaft and 70 extending through said slots, gears secured to the ends of said shaft, tracks presenting serrated upper edges adapted to be engaged by said gears, an endless member within said casing and attached to said shaft, and means 75 for moving said endless members.

JOHN DI PIAZZA.
